CLAIM

We claim, the ornamental design for a lighting fixture, as shown and described.

DESCRIPTION

FIG. 1 is a perspective view of a lighting fixture, showing our new design in a first embodiment;
 FIG. 2 is a front view thereof;
 FIG. 3 is a rear view thereof;
 FIG. 4 is a side view thereof;
 FIG. 5 is another side view thereof;
 FIG. 6 is a top view thereof;
 FIG. 7 is a bottom view thereof; and,
 FIG. 8 is a cross-sectional view as taken along section 8-8 of FIG. 2.

The broken-line disclosure in the views is understood to form no part of the claimed design.
